UNITED STATES PATENT OFFICE.

ALBERT F. FROUSSARD, OF ST. LOUIS, MISSOURI.

PORTABLE MILLING MACHINE.

Application filed January 29, 1927. Serial No. 164,386.

My invention relates to a portable milling machine and particularly to one adapted to mill the valve seats of slide valve engines. One object of my invention is to utilize the 5 valve chest of the engine as a base for the machine thus dispensing with large and heavy castings. Another object of my invention is to so construct the machine that it may be adjusted to valve chests of different sizes. Still another object of my invention is to so construct the device that the parts may be readily detached from each other so that they may be packed in small space for transportation.

In the accompanying drawings, which illustrate one form of milling machine made in accordance with my invention, Figure 1 is a front elevation of the machine, together with a portion of an engine to which it is 10 attached; the tool supporting and driving mechanism being removed; Figure 2 is an end view of the parts shown in Figure 1; Figure 3 is a section taken on the line 3—3 of Figure 7; Figure 4 is a section taken on the line 4—4 of Figure 1; Figure 5 is an enlarged section taken on the line 5—5 of Figure 1, the tool supporting and driving mechanism, also partly in section, being shown; Figure 6 is a front view of the tool 15 supporting and driving mechanism; Figure 7 is a section taken on the line 7—7 of Figure 5; and Figure 8 is a section taken on the line 8—8 of Figure 5.

The engine indicated at 10 is provided 20 with the usual valve chest 11 the cover of which has been removed to give access to the valve seat. Four lugs 12 are secured to the corners of the valve chest by bolts 13. Each of the lugs 12 is provided with an opening for the passage of a guide bar 14 which is secured by a set screw after the parts are adjusted. Adjacent to the lugs 12 at one end of the valve chest are a pair of clamp blocks 15 and at the other end a 25 pair of clamp blocks 16. Formed in each of the blocks 15 and 16 are a pair of openings at right angles to each other, one for the reception of one of the guide bars 14 and the other for the reception of a vertical brace rod 17. Set screws secure these rods and bars in the blocks. While I have shown the blocks 15 and 16 separate from the lugs 12 each block may be permanently secured to or formed integral with its adjacent lug.

Sliding on each of the guide bars 14 is a

pair of guide blocks 18 similar in form to the blocks 16 but each provided with only one set screw to secure it to one of the pairs of vertical guide rods 19. Travelling on the guide rods 19 is a carriage 20 for the tool 30 supporting and driving mechanism.

Formed on each of the clamp blocks 15 is a bearing 21 for a threaded feed rod 22. The threaded portion of each of these rods engages with a threaded lug on a yoke 23 65 engaging the guide rods 19. Sprocket wheels 24 on the rods 22 are connected by a sprocket chain 25 so that the two rods may be rotated in unison to move the carriage 20 laterally. A crank handle 26 may be applied to the square end of one of the rods 22 to rotate it. Mounted on the lower end of one of the guide bars 19 is an arm 27 having a bearing for a feed rod 28 the threaded portion of which engages 75 with a lug 29 on the carriage 20. A square end is provided on the rod 28 so that it may be engaged by the crank handle 26 to raise and lower the carriage 20.

Secured to the carriage 20 is a casting 30 80 in which is mounted a worm wheel 31. A worm 32 on a shaft 33 engages with the worm wheel 31. Mounted on the shaft 33 is a pulley 34 connected by a belt 35 with the pulley 36 of a motor 37 carried on the casting 30. A cutter bar 38 carrying a milling cutter 39 is keyed in the worm wheel so as to rotate therewith but to be capable of longitudinal movement with respect thereto. Formed in one side of the cutter bar is a 90 groove 40 for the reception of a feed screw 41. This feed screw is prevented from longitudinal movement relative to the bar by a lug 42 secured to the bar and its threaded portion engages with a feed block 43 having 95 a groove in its side sliding around an internal flange 44 carried by the casting 30. This construction allows the cutter bar to be rotated by the motor and at the same time provides accurate adjustment for depth 100 which is secured by rotating the feed bar through the crank handle 45.

My device is applied to the engine by bolting the lugs 12 to the corners of the valve chest after the cover had been removed, the 105 set screws in the lugs as well as those in the clamp blocks 15 and 16 and in the guide blocks 18 being first loosened to allow the device to be adjusted to the size of the valve chest. The set screws are now tightened so 110

that the parts will form a rigid frame work. It will be understood that sprocket chain 25 may be lengthened or shortened by inserting or removing links. The milling action of the device is the same as in any milling machine and need not be described.

Having fully described my invention, what I claim as new and desire to secure by Letters Patent of the United States is:

1. In a device of the class described, the combination with two pair of lugs adapted to be secured to the valve chest of an engine, of a pair of guide bars each adjustably carried by one pair of said lugs, a cross carriage slidably carried on said guide bars, a tool carriage slidably mounted on said cross carriage, and a milling tool mounted in said tool carriage.

2. In a device of the class described, the combination with two pair of lugs adapted to be secured to the valve chest of an engine, of a pair of guide bars each adjustably carried by one pair of said lugs, a second pair of guide bars extending at right angles to said first named pair and forming a cross carriage, adjustable connecting means between said pairs of guide bars, a tool carriage, sliding on said second set of guide bars, and a milling tool carried by said tool carriage.

3. In a device of the class described, the combination with two pair of lugs adapted to be secured to the valve chest of an engine, of a pair of guide bars each adjustably carried by one pair of said lugs, brace rods extending between said guide bars and adjustably secured thereto, and a tool carriage supported from said guide bars.

4. In a device of the class described, the combination with lugs adapted to be secured to the valve chest of an engine, of a pair of guide bars adjustably carried by said lugs, a second pair of guide bars slidably mounted on said first named guide bars and forming a cross carriage, yokes engaging said latter named guide bars, feed rods en-

gaging said yokes, means for simultaneously rotating said feed rods, and a tool carriage slidably mounted on said cross carriage.

5. In a device of the class described, the combination with lugs adapted to be secured to the valve chest of an engine, of a pair of guide bars adjustably carried by said lugs, a second pair of guide bars slidably mounted on said first named guide bars and forming a cross carriage, yokes engaging said latter named guide bars, feed rods engaging said yokes, and a tool carriage slidably mounted on said cross carriage.

6. In a device of the class described, the combination with lugs adapted to be secured to the valve chest of an engine, of a pair of guide bars adjustably carried by said lugs, a brace bar extending between said guide bars, clamp blocks adjustably securing said brace bar to said guide bars, feed rods carried by said clamp blocks, a cross carriage actuated from said feed rods, and a tool carriage sliding on said cross carriage.

7. In a device of the class described, the combination with lugs adapted to be secured to the valve chest of an engine, of a pair of guide bars adjustably carried by said lugs, a second pair of guide bars forming a cross carriage, adjustable means for securing said second pair of guide bars in sliding relation to said first named bars, a feed rod carried by one of said second named guide bars, and a tool carriage sliding on said cross carriage and actuated from said feed rod.

8. In a device of the class described, the combination with a tool carriage, of means for mounting said carriage on the valve chest of an engine, a casing mounted on said carriage, a cutter bar journaled in said casing, a feed screw passing through said cutter bar and engaging with a slotted feed block, and an internal flange carried by said casing and engaging the slot in said feed block.

In testimony whereof, I hereunto affix my signature, this 27 day of January, 1927.

ALBERT F. FROUSSARD.
